Ohio, a corporation of Ohio, as trustee

Application May 16, 1938, Serial No. 208,275

7 Claims. (Cl. 15—14)

The invention relates to suction cleaners and more particularly to a cleaner of the portable electrically operated type which may be selectively employed for floor cleaning purposes or for cleaning walls, ceilings, furniture and the like.

One of the objects of my invention is to provide in such a cleaner a porous filtering element and a stiff non-porous grooved receptacle for the filtering element.

Another object of my invention is to provide a light weight cleaner of attractive appearance and preferably streamlined in cross section.

Another object is to provide an improved receptacle, housing or caddy for the air filtering element of the cleaner so constructed as to permit air to flow readily through the receptacle after having passed through the filtering element.

Another object is to provide improved means whereby the dust contained in the air entering the filtering element passes close by the hand and before the eyes of the operator.

Another object is to provide improved connections between the filter carrying receptacle and the suction pipes with which the device is equipped.

A further object is to provide means whereby a vapor which may be a germicide, insecticide, deodorant or perfume may be supplied either to the atmosphere or to a definite location through an attachment to the cleaner.

Another object is to provide an improved applicator hood for applying the vapor intensively at a desired location.

Other distinctive features characterizing the invention will be apparent from a consideration of the accompanying drawings and the following detailed description in which are set forth for the purpose of illustration but not by way of limitation a specific embodiment of the invention.

In the drawings:

Fig. 1 is a side elevation of a portable suction cleaner provided with a corrugated bag holding receptacle, parts being broken away or shown in section to reveal the interior.

Fig. 2 is a fragmentary view showing the filtering bag, a portion of the bag receptacle and a portion of the suction pipe carried thereby.

Fig. 3 is a detail view of the crown piece or valve casing and hollow handle grip attached thereto, these parts being shown separated from the bag receptacle.

Fig. 4 is a detail end view showing an absorbent pad and vial of liquid associated therewith employed for supplying vapors to the atmosphere.

Fig. 5 is a top plan view of the face plate of the caddy or receptacle.

Fig. 6 is a section on line 6—6 of Fig. 1.

Fig. 7 is a plan view of a gasket to be inserted between the face plate and the crown piece.

Fig. 8 is a plan view looking downwardly on the crown piece shown in Fig. 3.

Fig. 9 is a longitudinal section of the transparent valve cap which regulates the flow of dust laden air into the dust bag.

Fig. 10 is a side elevation showing the cleaner supported in vertical position from a wall bracket, the hollow handle grip being equipped with suitable extension elements.

Fig. 11 is a plan view on a similar scale looking down on the cleaner of Fig. 1.

Fig. 12 is a fragmentary plan view showing the lower portion of the cleaner which is equipped with a hood for intensively applying vapors to a particular location.

Fig. 13 is a side view of the same.

Fig. 14 is a detail view on a smaller scale showing the hood itself separated from the cleaner.

Fig. 15 is a section on line 15—15 of Fig. 14.

Fig. 16 is a side elevation of a slightly modified form of cleaner similar to Fig. 1 except that the suction pipe leading from the floor tool is outside the bag receptacle instead of inside.

Fig. 17 is a section on line 17—17 of Fig. 16.

Fig. 18 is a detail view of one of the metal mounts or end rings of the cleaner housing or caddy.

Referring now in detail to the drawings and particularly to Figs. 1 and 6 thereof, the reference numeral 10 denotes a receptacle, housing or caddy for the filtering element 11. The receptacle is shown as elongated in form, oval or streamlined in cross section and provided with corrugations 12 herein shown as extending lengthwise thereof so that the filtering element contacts the receptacle only at the ridges of the corrugations, thus allowing air to pass immediately through the filtering element and increasing its filtering efficiency. The ribs and grooves formed by the corrugations are shown as both external and internal since this represents the simplest mode of manufacture but the important feature is that the corrugations should be on the inner surface although the external corrugations also add to the uniqueness and attractiveness of the appearance of the device as a whole.

The receptacle may be of any suitable lightweight material as for example fibrous material such as fiberboard or cardboard, in which the corrugations are formed in any desired or well known manner.

The receptacle may also be formed of any of the many types of plastic materials such as phenolic condensation products or the like, or may be formed of light weight metal, such as aluminum. Non-metallic material is preferred, however, both on account of its lightness and because it is a non-conductor of electricity. Where the caddy is formed of a fibrous sheet the entire weight of the caddy may be less than one-half pound while at the same time the structure possesses the advantages of necessary strength and resiliency. It will be obvious that the corrugations, in addition to aiding the filtering operation also add to the strength of the caddy. While the corrugations are illustrated as straight and parallel to the longitudinal axis of the cleaner, any embossments, channels, furrows, wrinkles, sinuosities, convolutions, undulations, waves, bumps, reliefs or other forms making passageways for filtered air are contemplated as within the broad scope of the invention.

At the upper end of the caddy or receptacle there is provided a face plate 13 best shown in Fig. 5, which is provided with a large opening 14 to receive the bag 11 and a smaller opening 15 to receive the end of a suction pipe 16 which extends longitudinally of the caddy. The face plate is provided with a downwardly extending rim or ring 17 shown in detail in Fig. 18, surrounding the upper edge of the caddy and serving to reinforce the same. The face plate may be secured to the caddy in any suitable manner.

As shown the rim or ring 17 is crimped so as to tightly engage the corrugated body portion 10 and suitable heat-hardening plastic sealing material may be employed to insure a fluid tight fit between the body portion 10 and the rim or ring 17. Such plastic may be of the phenolic condensation type, or of any of the numerous other types of heat-hardening plastics.

The filtering element 11 may be of any desired material as for example porous paper, cloth or fine mesh wire or the like. Where paper is employed the same may be reinforced with a coarser mesh fabric if desired although such reinforcement is not considered absolutely essential. The filtering element is shown as in the form of a bag which extends nearly to the bottom of the caddy and is provided at its mouth portion with an outwardly extending flange 18 which fits snugly against the face plate 13.

A crown member 19 best shown in Figs. 3 and 8 is adapted to be fitted over the face plate 13 and when secured in place serves to clamp the flange 18 of the bag against the face plate 13 with a fluid tight fit. To insure such a fit a suitable gasket 20 (Fig. 7) is preferably interposed between the crown member and the face plate. The crown member is shown as oval in cross section and as composed of light weight material. Such material may be transparent as in the case of Celluloid or molded condensation products. Molded fibre or light weight metal such as aluminum may be employed. The flat lower face portion 21 of the crown piece is adapted to bear against the gasket 20 or against the flange 18 of the bag if the gasket is omitted. The crown piece is ported and is provided with a large central open portion or chamber 22 having an inlet 23 which communicates with the longitudinally extending suction pipe 16, and an inlet 24 which communicates with a hollow handle grip member 25 which may be provided with any suitable extension members as illustrated in Fig. 10. The

crown piece also includes a central outlet or nipple 26 which is adapted to communicate with the interior of the filter bag and projects a short distance into the same. If it is desired to have the bag removable with the crown piece the neck of the bag may be secured to the nipple 26 by any suitable fastening means.

The crown piece constitutes the casing portion of a valve the movable member of which is the cap shown in Fig. 9 which is provided with a transparent domed top 27 and a circular flange portion 28 secured to the top at 29. The flange 28 is adapted to fit into circular opening 22 in the crown piece and is provided with a lateral opening 30 which is adapted to be placed in communication with either of the inlets 23 or 24 to permit dust laden air to flow therethrough into the cleaner bag, the other inlet being at the same time cut off by the unperforated portion of the flange. Thus dust laden air may be drawn into the filtering bag either from the pipe 16 extending longitudinally of the receptacle 10 or through the curved hollow handle 25 according to the position of the valve cap. It will be noted that the transparent valve cap and the crown members are located close to the hand of the operator and one of the attractive features of the apparatus is the effective view of the dust right by the hand and before the eyes of the operator. The transparent top 27 may be provided with an arrow or other indicator 31 which points toward the opening 30 so that the operator may know when the valve is properly located with reference to the inlets 23, 24.

Any suitable means may be provided for clamping the crown member 19 in place. As shown a projection 32 on the crown piece fits into an opening 33 in a securing member 34 carried by the rim 17 of the face plate 13, while another projection 35 at the rear of the crown member is adapted to be engaged by a clamping ring 36 also carried by the rim of the face plate.

The suction pipes 16 and 25 may be made of any suitable materials, preferably non-conductors of electricity, as for example hard fibre or molded synthetic materials, although light weight metals may be employed if desired, if care is exercised to properly insulate the electric conduits, etc. Any suitable extension devices may be connected with either of the suction pipes. The handle 25 may be provided with a latch member 37 by means of which the cleaner may be supported in upright position.

The pipe 16 is shown as extending lengthwise of the cleaner, in Fig. 1 being enclosed within the bag receptacle 10, while in Fig. 16 the pipe 16' is located externally of the receptacle 10'. The arrangement shown in Fig. 1, however, is generally preferred as the cleaner with the longitudinally extending pipe enclosed presents a neater appearance and is easier to keep clean.

In the arrangement shown in Fig. 1 it will be noted that the pipe 16 extends between the face plate 13 at the upper end of the caddy or receptacle and a somewhat similar member 38 at the base of the receptacle which member is provided with an opening (not shown) to receive the lower end of the suction pipe 16 and with a much larger opening (not shown) to permit passage of filtered air into the power plant 39. The rim of member 38 may be crimped and secured to the caddy in a manner similar to rim 17.

Projecting beyond the lower member 38 is an extension 40 of the pipe 16, which may be a sep-

arate section of pipe or may be integral with the pipe 16. The extension 40 is shown as curved at its lower end to fit the curvature of the power plant casing to which it is rigidly secured by means of a strap 41. A stub pipe 42 fits over the lower end of the extension 40 and is rotatably connected by means of an inclined joint 43 to an elongated floor tool or nozzle 44 having supporting end rollers 45 to permit the cleaner to be moved to and fro across the floor. The floor tool herein disclosed may be replaced by other extension devices which are easily applied to the lower end of the pipe 40.

The power plant 39 is detachably secured at the lower end of the caddy and comprises a suitable electric motor or motors and fan or fans driven thereby, the details of which are not shown. Electric current may be supplied to the motor through a suitable control cord 55 which may pass down through the interior of the caddy to the motor or motors. The power plant casing is shown as provided with a pair of like laterally extending outlet pipes 52, 52 for discharging air from the fan or fans. Either of these pipes is large enough to carry the entire exhaust from the cleaner and either or both may be equipped with a blower extension. Where only one is used the other may be plugged if desired without interfering with the free flow of air.

When it is desired to apply suitable vapors to the atmosphere or to a surface being treated this may be accomplished by the use of a pad 46 of porous material impregnated with a volatile deodorant, germicide, insecticide or perfume, the pad being preferably located between the filter bag and the power plant as best shown in Fig. 1. The pad itself may be protected on opposite sides by screening 47 and may be provided with wicking (not shown) extending into a vial 48 shown as carried by the cleaner and which contains the volatile liquid to be vaporized.

When it is desired to apply the vapors intensively to a particular location an applicator hood 49 such as is shown in Figs. 12 to 15 inclusive may be employed. This hood may be of any suitable material, preferably rubber, and is arranged to fit over the floor tool 44 with the stub outlet portion 42 of the tool projecting through a central opening 50 at the upper rear portion of the hood.

A pair of flexible hollow arms 51, 51 carried by the hood are adapted to fit over the lateral exhaust or blower outlets 52, 52 leading from the power plant. When the applicator hood is in use the indicator arrow 31 on the valve cap 27 at the upper portion of the cleaner is turned in the position at which air will be drawn into the apparatus through the handle 25 rather than through the floor tool. The floor tool during the period when the applicator is in use serves primarily as a wheeled support for said hood.

The widely diverse uses and advantages of the present apparatus will be largely apparent from the foregoing description, some of which will now be briefly described by way of summary.

When the device is to be used for ordinary floor cleaning purposes the apparatus will be supported at about a 45 degree angle as illustrated in Fig. 1, the indicator arrow 31 on the valve cap being pointed toward the opening 23 communicating with the suction pipe 18 to which the floor tool 44 is connected and the fan motor or motors are then started. The apparatus may be moved to and fro across the floor using the suction pipe 25 as a handle, the weight of the

apparatus being supported principally by the end rollers 45 of the floor tool. The cleaner may be equipped with suitable head lights 56, 56 one being shown on each side of pipe 40 and being provided with hoods arranged to direct the light upon the floor just in front of the floor tool nozzle. Such lights facilitate the cleaning operation particularly when it is desired to reach dark, out of the way corners. The dust laden air passes from the floor tool through the pipe 16 into and through the filter bag 11 which when inflated contacts the ridges of the receptacle 10 so that substantially the entire surface of the bag is effectively utilized for filtering purposes. The filtered air passes to and through the power plant and out through the lateral openings 52, 52. When the pad 46 is employed and is saturated with a volatile liquid the vapor passes with the air from the outlets and into the atmosphere. Hose pipes or the like (not shown) may be attached to the outlets 52 and directed to any desired location.

When it is desired to apply the vapor intensively to the floor or other surface, the floor cleaning tool 44 is first removed and the applicator hood 49 fitted thereover. Then the floor tool with the hood mounted thereon is replaced and the arms 51, 51 of the applicator hood are fitted to the lateral outlets 52, 52 leading from the power plant. The valve cap 27 is rotated so that the arrow 31 points toward the handle 25 whereupon the motor is started and the apparatus moved to and fro across the floor or other surface. The vapors are applied in concentrated form by means of the applicator hood.

When it is desired to use the pipe 25 for suction purposes, the cleaner may be inverted and supported by the floor tool as a handle and the mouth of the pipe 25 directed to the proper location. The dust laden air will then be drawn into the dust bag through the suction handle and filter. If desired the cleaner may be supported in the 45 degree angle position and suitable extension devices attached at the end of the pipe 25.

The cleaner may also be supported in the upright position as shown in Fig. 10 wherein it occupies a minimum of space. The handle 25 is shown as supported by a flexible bracket 60 extending outwardly from the wall. To the end of the handle an L-connector member 61 may be secured and a flexible tube or tubes 62 having a nozzle 63 may be fitted to the connector. The device may be operated in the upright position as a stationary cleaner, the conductor 55 being plugged into a socket in the wall and the motor started. The nozzle 63 on the end of the hose 62 may be moved to any desired location for cleaning purposes. The hose 62 may be as long as needed and extra lengths may be employed sufficient to reach all parts of the room or into adjacent rooms without moving the cleaner. The apparatus may also be supported at the 45 degree angle resting jointly upon the floor tool rollers 45 and the rollers 64, 64 carried by a spring bracket 65 hingedly secured at 66, 66 to pins on the rim of the plate 38 at the bottom of the caddy. The bracket may also be hingedly secured to ears 67 located at a higher level on the rim or plate 38. If the cleaner is supported upright against the wall as in Fig. 10 the bracket 65 may be folded downwardly so as to be out of the way.

When the air filter is full of dust the crown piece 19 and handle 25 may be removed as indi-

cated in Fig. 3 whereupon the bag is accessible. The bag may then be emptied or destroyed, depending on the type of material used. Where cheap porous paper is employed it may be desirable to burn the bag together with its contents while where more expensive material is used it may be preferable to empty the same. If the mouth of the bag be secured to the nipple 26 it may be withdrawn as a unit with the crown piece and handle. In such case it may be subsequently 10 separated therefrom and either emptied or replaced by another bag.

The invention has been described in detail for the purpose of illustration but it will be apparent that numerous modifications and variations may 15 be resorted to without departure from the spirit of the invention as will be apparent to those skilled in the art.

I claim:

1. In a suction cleaner, in combination, a stiff fluid-tight tubular outer casing provided throughout its interior with fixed closely spaced projections, and having an inlet for dust laden air, and an outlet adapted to be connected to a source of suction, a removable air filtering bag having its open end fitting the air inlet, said bag being adapted when inflated to contact said projections only, leaving air passages between the bag and the inner wall of the casing whereby a free flow of air from the casing inlet through the 30 bag and to the casing outlet is insured at all times.

2. In a suction cleaner, in combination, a fluid-tight tubular casing having an inlet adapted to be connected to a conduit through which dust laden air may be drawn and an outlet adapted to be connected to a source of suction, an air filtering bag having its open end closely fitting the casing inlet, and being adapted when expanded to closely fit the interior of the casing, said casing being provided throughout its entire area with fixed spaced internal projections, whereby contact between the bag and the wall of the casing is prevented except at said projections and a free flow of air is insured.

3. In combination, a stiff non-porous elongated outer casing having an inlet end adapted to be connected with a conduit through which dust laden air may be drawn and having an outlet end adapted to be connected with a source of suction, said casing being formed with fixed longitudinally extending corrugations, an air filtering bag having its open end positioned closely adjacent the inner periphery of said inlet end and having its side portions contacting the inner wall of said casing only at the ridges of the inwardly extending portions of said corrugations under the influence of air pressure, whereby air passageways are provided between said bag and said inner wall.

4. In combination, a stiff, non-porous, elongated, internally longitudinally corrugated receptacle, an air filtering bag shaped to conform to the general shape of the interior of said recep-

tacle and of a size to allow its side walls to contact the inwardly extending corrugations under the influence of air pressure, said bag being connected at its open end to means at one end of said receptacle providing a suction inlet, the other end of said receptacle communicating with a source of suction, a suction pipe extending longitudinally within and adjacent a side wall of said receptacle along the entire length of said bag whereby said pipe cooperates with said internal corrugations in providing longitudinally extending air channels within said bag, said suction pipe being at its lower end connected with a floor tool and at its upper end connected with means providing communication with said suction inlet.

5. In a suction cleaner, a hollow handle grip portion, an air filter, a stiff non-porous receptacle for said filter communicating at one end with a source of suction, a top plate for said receptacle having a large opening to permit insertion of said filter and a smaller opening adjacent the larger opening, said filter having a flange at its mouth portion resting on said top plate, a suction pipe extending lengthwise of said receptacle with one end passing through the smaller opening, an open topped valve casing member supported upon said plate, and having three other openings, one communicating with the interior of said filter, a second communicating with said longitudinally extending pipe, and a third communicating with a hollow handle grip portion, and a rotatable valve cap member fitting the top of said casing, and adapted to be moved to selectively connect either the longitudinally extending pipe or the handle grip portion with the interior of the filter.

6. The combination with a suction cleaner comprising an air filtering element, a non-porous elongated receptacle for said filter, suction producing means connected at one end of said receptacle, and having a pair of laterally extending blower outlets, a suction pipe adapted to be placed in communication with said filtering element, and a floor tool at the end of said pipe; of a pad impregnated with volatile matter interposed between the filter and said suction producing means and an applicator hood for intensively applying the vapors from said pad having a pair of hollow arms fitting over the blower outlets of said suction producing means, said hood being adapted to fit over said floor tool and having an opening to permit the suction pipe leading to the floor tool to pass therethrough.

7. An applicator hood adapted to fit over an elongated floor tool of a suction cleaner, said hood having an opening to fit the outlet pipe of the floor tool, and having a pair of hollow arms adapted to fit a pair of blower outlet pipes projecting laterally from the suction cleaner power plant.

DANIEL BENSON REPLEGLE.
